UNITED STATES PATENT OFFICE.

GEORGE L. DENNERLINE, OF AURORA, INDIANA.

SAFETY-BELT.

No. 927,839.

Specification of Letters Patent.

Patented July 13, 1909.

Application filed January 12, 1909. Serial No. 471,959.

To all whom it may concern:

Be it known that I, GEORGE L. DENNERLINE, a citizen of the United States, residing at Aurora, in the county of Dearborn and 5 State of Indiana, have invented certain new and useful Improvements in Safety-Belts, of which the following is a specification.

This invention comprehends certain new and useful improvements in safety belts of 10 that type designed to be worn under the clothing and adapted to contain money, jewels or other similar valuables, and the invention has for its object an improved device of this character which embodies one or more 15 receptacles for carrying the valuables and which also includes an improved clasp that connects together the ends of the belt to secure the same in position and that also serves to normally maintain the receptacle closed 20 to prevent the possible abstraction of the valuables therefrom, the clasp being quite difficult to manipulate, so as to render necessary the disturbing of the wearer, and thus insure against the surreptitious removal of 25 the belt in event of the wearer being asleep.

With this and other objects in view that will more fully appear as the description proceeds, the invention consists in certain constructions and arrangements of the parts 30 that I shall hereinafter fully describe, and then point out the novel features thereof in the appended claims.

For a full understanding of the invention and the merits thereof, and to acquire a 35 knowledge of the details of construction, reference is to be had to the following description and accompanying drawing, in which:

Figure 1 is a top plan view of a safety belt constructed in accordance with my invention; Fig. 2 is a longitudinal sectional view 40 thereof, showing one of the receptacles and the clasp therefor; Fig. 3 is a fragmentary perspective view, showing the clasps opened; Fig. 4 is a perspective view of one of the 45 receptacles; Fig. 5 is a transverse section thereof; and, Fig. 6 is a fragmentary perspective view of the inner wall of one of the receptacles.

Corresponding and like parts are referred 50 to in the following description and indicated in all of the views of the drawing by the same reference characters.

My improved device consists essentially of 55 a metallic belt 1 which is of any length according to the size of the waist of the wearer and which, in the present instance, is in the

form of a chain composed of substantially flat links so as to conform more readily to the lines of the body and cause the wearer no discomfort.

60

The chain is equipped with any number of treasure boxes 2, according as found most desirable in practice, although in the present instance, I have illustrated only two of such boxes to the opposite ends of which the extremities of the chain belt are permanently affixed in any approved manner. These boxes are constructed of metal such as sheet steel, and may be of any desired shape or design, although they are preferably relatively 65 thin, as shown, and have their various faces of substantially rectangular form. The opposing ends of the boxes are provided with outstanding ears 3 that are transversely slotted, as indicated at 3^a, while the inner 70 walls of the boxes, that is, the walls adjacent to the body, are broken away to form openings 4 to afford access to the interior of the respective boxes and permit the valuables to be inserted therein or withdrawn 75 therefrom. These openings lead from the inner ends of the boxes, and terminate short of the opposite ends thereof, the openings also extending entirely between the side walls of the boxes that are formed with outstanding flanges 5 which are arranged for engagement with the returned longitudinal edges 6 of plates 7 to slidably and detachably connect the same to the respective 80 boxes. These plates normally extend over 85 the respective openings 4 to completely close the boxes, and the plates are of such length that when in such position, they project longitudinally beyond the adjacent ends of the boxes, as best seen in Fig. 3, the 90 projecting portions of the plates being formed with transverse slots 8 adapted for registry with the slots 3^a of the ears.

Interposed between the boxes 2, are two clasps 9, there being one clasp for each box, 100 and the clasps being substantially duplicate in structure, as will be readily observed by reference to the drawing. Each of these clasps consists of two leaves or members 10 and 11, which are hingedly connected together by a transversely disposed pintle 12 and one of which, designated 11, is relatively shorter than the other. The shorter leaf 11 is designed to be passed through the corresponding registering slots 3^a and 8, and 110 the free end of such leaf is then swung toward the longer leaf 10 and is designed to be held

thereto with the connected ends of the leaves and the pintle 12 positioned in the registering slots to prevent any movement of the closing plate 7 relative to the box. As the 5 preferred means for detachably holding the shorter leaf 11 against the other leaf to close the clasp, I employ a collar 13 that encircles the latter leaf and is mounted for longitudinal movement thereon, said collar being 10 adapted to be slid toward the adjacent box to engage the free end of the leaf 11 that is slightly reduced in thickness, as illustrated in Fig. 2. The two clamps just described are hingedly connected together through the 15 instrumentality of a link 14 through which pass the returned adjacent ends of the leaves or members 10, the said returned ends being located at the opposite faces of the leaves 10 from those against which the leaves 11 are 20 arranged to lie when in closed position, and the longitudinal distance between the extremity of the returned portion and the free end of the leaf 11 being less than the length of the collar 13, for a purpose to be 25 presently disclosed.

In the practical use of my improved safety belt, the same is applied to the waist of the wearer and is held in position thereon by means of the two clasps 9 which are engaged 30 with the respective boxes 2 and also serve to maintain the boxes securely closed to retain the valuables therein. Should occasion demand the removal of the valuables from one of the boxes, or the opening of such box for 35 any other purpose, it will be readily apparent that in order to effect such opening it is necessary to release the shorter leaf or member 11 of the corresponding clasp 9 before the clasp may be disengaged from the registering 40 slots 3^a and 8 to unlock the plate 7. The corresponding collar 13 is therefore slid longitudinally on the longer member 10 and toward the link 14, but inasmuch as the distance between the swinging end of the leaf 11 and the returned end 15 is less than the 45 length of the collar, and since the returned end is too thick to permit the collar to be moved thereon, such returned end limits the desired movement of the collar and prevents the ready release of the member 11. It 50 therefore becomes necessary to move the collar some distance on the leaf 10, with a portion of the former wedged in between the latter and the corresponding returned end 55 15, and since this requires considerable manipulation, it will be obvious that the detachment of the belt could not be effected without awaking the wearer, in case he was asleep. The release of the leaf 11 admits of 60 the clasp being quickly disengaged from the slots 3^a and 8 to disconnect the opposite ends of the belt to admit of the latter being removed from position, and also simultaneously unlocks the plate 7 so that the latter may be 65 slid longitudinally of the box to afford access

to the interior thereof. The belt is returned to position by reversing the operation just described.

From the foregoing description, in connection with the accompanying drawing, it will be apparent that I have provided an improved belt, the parts of which are constructed entirely of metal so as to preclude the possibility of the belt being cut to remove the same from the wearer in an attempt to 70 steal the valuables; which is provided with several treasure boxes that, in the normal position of the belt, are maintained securely closed and that may be quickly opened by the wearer when desired; which may be worn beneath the clothing and during both the day and night without subjecting the wearer to discomfort or inconvenience; and which possesses certain other advantages that will further recommend the belt to those using 80 such articles.

Having thus described the invention, what I claim is:

1. The combination of a belt, a receptacle disposed thereon and formed with an opening, a closure for the opening, and means carried by the belt and engaging both the receptacle and the closure to secure the latter over the opening. 90

2. The combination of a belt, a receptacle for valuables disposed thereon, means independent of the belt for closing the receptacle and means carried by the belt for engaging both the receptacle and the closing means. 95

3. The combination of a belt, a receptacle disposed thereon and formed with an opening, a closure for the opening, and a clasp carried by the belt and detachably engaging both the receptacle and the closure to secure the latter over the opening. 100

4. The combination of a belt, a receptacle secured at one end thereof and formed with an opening, a closure for the opening, the closure and the receptacle being formed with slots adapted to register, and means carried 110 at the opposite end of the belt for engaging the registering slots.

5. The combination of a belt, a receptacle secured thereto and formed with an opening and with an outstanding ear, a closure for the opening, arranged to overlap the ear, and a clasp carried by the belt and adapted to be engaged with both the ear and closure to secure the latter to the receptacle. 115

6. The combination of a belt, a receptacle secured thereto and formed with an opening, a closure for the opening, a clasp carried by the belt and comprising a leaf, and a second leaf pivotally connected at one end to the first named leaf and adapted to be passed into engagement with both the closure and the receptacle, and means for connecting the free end of the last named leaf to the first named leaf to maintain the clasp closed. 125

7. The combination of a belt, a receptacle 130

secured thereto and formed with an opening, a closure for the opening, a clasp carried by the belt and comprising two leaves or members, one relatively shorter than the other 5 and pivotally connected at one end thereto, the shorter member being adapted to be passed into engagement with both the receptacle and the closure and swung against the other member, and means for connecting 10 the free end of the shorter member to the longer member to maintain the clasp closed.

8. The combination of a belt, a receptacle secured thereto and formed with an opening, a closure for the opening, a clasp carried by 15 the belt and comprising two leaves or members, one relatively shorter than the other and pivotally connected thereto, the shorter member being adapted to be passed into engagement with both the closure and the receptacle and then swung against the other member, a collar slidably mounted upon the longer member and adapted to engage the free end of the shorter member.

9. The combination of a belt, a receptacle 25 secured thereto and formed with an opening, a closure for the opening, a clasp carried by the belt and comprising two leaves or members, one relatively shorter than the other and pivotally connected at one end thereto, 30 the longer member being returned upon itself at its opposite end, and the shorter member being adapted to be passed into engagement with both the receptacle and the closure and swung back against the longer member, and a collar mounted on the longer member and adapted to engage the free end 35 of the shorter member, the free end of the shorter member being relatively thinner than the returned end and being spaced therefrom 40 in closed position, less than the length of the collar.

10. The combination of a belt, receptacles secured to the ends thereof and formed with 45 openings, closures for the openings, clasps interposed between the receptacles and hingedly connected together, each clasp consisting of two members or leaves hingedly connected together and adapted to be passed into engagement with both the receptacle and the 50 closure therefor, and means for holding the clasps in such engagement.

11. The combination of a belt, a receptacle connected thereto and formed with an opening, means for closing the opening, a clasp carried by the belt and embodying hinged 55 leaves arranged to be engaged with both the receptacle and the closure therefor.

12. The combination of a belt, a receptacle carried thereby and provided with an opening, means for closing the opening, said closing means being arranged for sliding connection with the receptacle, and means disposed on the belt for engaging both the closing means and the receptacle to secure the former to the latter.

13. The combination of a belt, a receptacle carried thereby and provided with an opening, means for closing the opening, said closing means having a detachable connection with the receptacle and means disposed on 70 the belt for engaging both the closing means and the receptacle to secure the former over the opening.

14. The combination of a belt, a receptacle disposed thereon and provided with an opening, a plate for closing the opening and means carried by the belt for engaging both the receptacle and the plate.

15. The combination of a belt, means for detachably connecting the ends thereof, a receptacle carried by the belt, a closure for the receptacle, the said connecting means engaging both the receptacle and the closure to secure the latter over the opening.

16. The combination of a belt, receptacles 85 secured thereto, closures for the receptacles and a detachable connection between the receptacles, said connection engaging the closures to maintain the same in operative relation to the respective receptacles.

17. The combination of a belt, receptacles secured thereto, closures for the receptacles, and a detachable connection between the receptacles, said connection embodying clasps adapted for engagement with the respective 95 receptacles and the closures thereof.

In testimony whereof I affix my signature in presence of two witnesses.
